6 Claims. (Cl. 211—47)

The present invention concerns an apparatus for selectively displaying suspended carpets, rugs and the like.

It is one object of the invention to improve prior art carpet or rug display apparatus to permit safe and convenient handling by one single person.

It is another object of this invention to provide novel and improved devices for exhibiting rugs and carpets which make it possible to expose to view the entire surface of a rug or carpet rather than but one half of the surface thereof.

It is another object of this invention to provide novel and improved devices for exhibiting rugs and carpets which devices are predicated upon a novel rug-handling and rug-manipulating concept which will be set forth below more in detail.

The novel features that are characteristic of the invention are set forth in particular in the appended claims. The invention itself, however, both as to structure and operation together with additional objects and advantages thereof will best be understood from the following detailed description of a preferred embodiment thereof when read in connection with the accompanying drawing in which:

FIG. 1 is a side view of an apparatus embodying the invention having one single rug supporting frame;

FIG. 2 is a top plan view of the left portion of the structure of FIG. 1 including several rug-supporting frames;

FIG. 3 is an enlarged horizontal section of a detail of the structure of FIGS. 1 and 2, namely of a bracket;

FIG. 4 is an enlarged fragmentary elevational detail of a guide bearing forming part of the structure of FIGS. 1 and 2; and

FIG. 5 is a cross-section of the detail shown in FIG. 4.

Reference character 1 has been applied to indicate an upright column 1 mounted on a base 2 preferably provided with rollers (not shown). The horizontal brackets 3 formed of angle iron are fixedly mounted on the column 1. Brackets 3 are provided with one or more circular holes 3a. An upright guide rod 5 is mounted in each of holes 3a formed in the brackets 3. Reference character 4a has been applied to indicate a plurality of pairs of bearings each supporting a frame 4 which is rectangular in shape when seen in side elevation. Each frame 4 is formed of several rods, and adapted to be displayed upwardly and downwardly, a distance which is approximately equal to the height of the frame. The upper rod or rods of the frames 4 serve to suspend two rugs or carpets. This may be effected by means of suspension clips 4b fitted to their upper edges, or by means of a clamping bar. Both rugs or carpets are thus entirely exposed to view in the position of the device shown in solid lines in FIG. 1. When it is intended to exhibit a rug frame 4 is moved downward along its guide rod 5 to the lower position, shown in broken lines in FIG. 1. A concave double rug-support 4d may be pivotally supported on a lower horizontal frame rod 4c of each frame 4. Rug-support or roll-support 4d is intended to receive rugs which are still entirely rolled-up, or at least in part rolled-up, as will be explained below more in detail. If desired rug-support 4a may be arranged somewhat higher than shown in FIG. 1 so that a rolled-up rug resting on

2

support 4d completely exposes the lower frame rod 4c. To so position rug-support 4d an additional rod (not shown) may be arranged above the lower frame rod 4c and the double rug-support or roll-support 4d may be 5 pivotally supported by the first mentioned rod.

When a rug-loaded frame 4 is moved upwardly along guide rods 5, it must be fixedly held in position at a desired level. This may be effected in one of numerous ways. In the embodiment of the invention shown in the 10 drawing each guide rod 5 is provided with a horizontal bore into which a pin 5a is inserted. The pin 5a is in the form of a hairpin, including an outer limb 5b having a bend 5c whose shape conforms to the cylindrical surface of the rod 5. The outer limb 5b of pin 5a is relatively heavy causing the latter to assume the position shown in FIG. 4. A plurality of notches 4e are provided on the lower side of the lower bearing of each pair of bearings 4a. Hence each supporting frame 4 can be locked in its angular positions upon having been pivoted 20 about its respective guide rod 5.

Owing to the considerable weight of rugs or carpets, to which the tubular guide rods 5 are subjected, it is desirable to provide for the latter additional bracing means. According to FIG. 3 an additional angular bearing bracket 3 is provided in the centre between the lower and the upper bearing bracket 3. Centre bracket is provided with U-shaped slots 3b open towards the right, each engaging one of the guide rods 5.

When mounting a guide rod 5 on column 1, the upper 30 end is first pushed through the hole of the top bracket 3 until its lower end is situated over the corresponding registering hole of the lower bracket 3 into which it then drops. This freedom of movement prevails on account of the U-shaped slots 3b of the centre bracket 3. In 35 order to secure the guide rods 5 when inserted into bracket 3, a gate member 6 is mounted above the central bracket 3 which extends transversely across all the guide rods 5 and prevents them from being moved out of slots or recesses 3b. Gate member 6 is supported directly on the centre bracket 3 and is shown in FIG. 1 at a somewhat higher level than it should actually be arranged in order to separate it clearly from centre bracket 3.

The column 1 may be adapted to be secured to the wall of a room. It may be replaced entirely by the wall of a room, in which case brackets 3 are mounted directly on the wall.

In operation one of the rug-supporting frame structures 4 is lowered until its upper edge is approximately at the eye-level of an erect or standing person. Thereupon one edge of the rolled-up rug or carpet remaining on the floor level is raised and secured to the upper edge of the lowered frame structure. The lower portion of the rug or carpet remains initially rolled-up and rests on the concave rug-support 4d which has been pivoted 90 degrees out of the plane defined by frame structure 4. After the upper edge of the rug has been firmly secured to the upper edge of the frame structure 4 the frame structure is raised to the position shown in FIG. 1 in solid lines. The task of raising the rug is relatively easy because each rug-supporting frame structure 4 can be raised or lowered separately, or individually. The lower half or portion of the rug remains in its rolled-up position on the concave rug-support 4d until the upper edge of the rug or carpet and of the frame structure 4 have reached their upper limit position, or highest elevation. Thereupon rug-support 4d is pivoted 90 degrees into the plane defined by frame structure 4, thus allowing the lower half of the rug or carpet to unroll and to drop to the floor. Now the rug is ready to be viewed in its entirety, i.e. the entire surface of the rug rather than but half of its surface is exposed to view.

Each frame structure 4 may support a pair of rugs or

carpets arranged back to back whose front sides are exposed to view in their entirety.

What I claim is:

1. A device for exhibiting rugs and carpets comprising in combination:

- (a) a pair of superimposed brackets each extending substantially horizontally and each defining a plurality of holes, one of each of said plurality of holes in the upper of said pair of brackets and one of each of said plurality of holes in the lower of said pair of brackets being arranged in registry;
- (b) common means for supporting said pair of brackets in fixed spaced relation;
- (c) a plurality of vertical supporting rods each projecting through one of said plurality of holes defined by the upper of said pair of brackets and each projecting through one of said plurality of holes defined by the lower of said pair of brackets;
- (d) a plurality of pairs of superimposed bearings, each of said plurality of pairs of bearings being slidably mounted on one of said plurality of supporting rods;
- (e) means for fixedly securing the lower of each of said plurality of pairs of bearings to a point on one of said plurality of supporting rods; and
- (f) a plurality of substantially flat frame structures each having one side juxtaposed to one of said plurality of supporting rods and each being supported by one pair of said plurality of pairs of bearings.

2. A device as specified in claim 1 comprising a plurality of roll-supports open at the upper side thereof, each of said plurality of roll-supports having a pair of concave roll-supporting surfaces and each of said plurality of roll-supports including a vertical pivot means arranged between said pair of surfaces and pivotally securing each of said plurality of roll-supports to one of said plurality of frame structures adjacent the lower side thereof.

3. A device for exhibiting rugs and carpets comprising in combination:

- (a) a pair of superimposed brackets each extending substantially horizontally and each defining a plurality of holes, one of each of said plurality of holes in the upper of said pair of brackets and one of each of said plurality of holes in the lower of said pair of brackets being arranged in registry;
- (b) common means for supporting said pair of brackets in fixed spaced relation;
- (c) a plurality of vertical supporting rods each projecting through one of said plurality of holes defined by the upper of said pair of brackets and each projecting through one of said plurality of holes defined by the lower of said pair of brackets;
- (d) a plurality of pairs of superimposed bearings, each of said plurality of pairs of bearings being slidably mounted on one of said plurality of supporting rods;
- (e) means for fixedly securing the lower of each of said plurality of pairs of bearings to a point on one of said plurality of supporting rods;
- (f) a plurality of substantially flat rectangular frame structures each supported by one of said plurality of pairs of bearings and each extending in cantilever fashion away from one of said plurality of supporting rods; and
- (g) a plurality of roll-supports open at the upper side thereof, each of said plurality of roll-supports being secured to one of said plurality of frame structures adjacent the lower side thereof and each of said plurality of roll-supports having a concave roll-supporting surface.

4. A device for exhibiting rugs and carpets comprising in combination:

- (a) a pair of superimposed brackets each extending substantially horizontally and each defining a plurality of holes, one of each of said plurality of holes in the upper of said pair of brackets and one of each

5. A device for exhibiting rugs and carpets comprising in combination:

- (a) a platform;
- (b) a vertical column having a predetermined height arranged adjacent one edge of said platform and supported by said platform;
- (c) a pair of superimposed brackets extending substantially parallel to said platform and supported by said column, one of said pair of brackets being arranged adjacent the top of said column and the other of said pair of brackets being arranged adjacent the bottom of said column, each of said pair of brackets defining a plurality of holes, one of each of said plurality of holes defined by said one of said pair of brackets and one of each of said plurality of holes defined by said other of said pair of brackets being arranged in registry;
- (d) a plurality of supporting rods substantially equal in length to said predetermined height extending parallel to said column and having lower ends resting on said platform, each of said plurality of supporting rods projecting through one of each of said plurality of holes defined by said one of said pair of brackets and each of said plurality of supporting rods projecting through one of said plurality of holes defined by said other of said pair of brackets;
- (e) a plurality of pairs of superimposed bearings, each of said plurality of pairs of bearings being slidably mounted on one of said plurality of supporting rods and having a smaller spacing than said predetermined height;
- (f) means for fixedly securing the lower of each of said plurality of pairs of bearings to a point on one of said plurality of supporting rods; and
- (g) a plurality of substantially flat rectangular frame structures each supported by one of said plurality of pairs of bearings and each extending in cantilever fashion away from one of said plurality of supporting rods and across said platform, each of said plu-

of said plurality of holes in the lower of said pair of brackets being arranged in registry;

(b) common means for supporting said pair of brackets in fixed spaced relation;

(c) a plurality of vertical supporting rods each projecting through one of said plurality of holes defined by the upper of said pair of brackets and each projecting through one of said plurality of holes defined by the lower of said pair of brackets;

(d) a plurality of pairs of superimposed bearings, each of said plurality of pairs of bearings being slidably mounted on one of said plurality of supporting rods;

(e) means for fixedly securing the lower of each of said plurality of pairs of bearings to a point on one of said plurality of supporting rods;

(f) an additional bracket supported on said common means extending substantially horizontally and arranged at a level situated between said pair of brackets, said additional bracket having a plurality of substantially U-shaped recesses each receiving one of said plurality of supporting rods;

(g) a gate member extending transversely across said plurality of supporting rods firmly maintaining said plurality of supporting rods inside said plurality of recesses;

(h) a plurality of frame structures each supported by one of said plurality of pairs of bearings and each extending in cantilever fashion away from one of said plurality of supporting rods; and

(i) a plurality of roll-supports open at the upper side thereof, each of said plurality of roll-supports having a pair of concave roll-supporting surfaces and each of said plurality of roll-supports including a vertical pivot pin arranged midway between said pair of surfaces and pivotally securing each of said plurality of roll-supports to one of said plurality of frame structures adjacent the lower side thereof.

rality of frame structures having a height substantially less than said predetermined height.

6. A device for exhibiting rugs and carpets comprising in combination:

- (a) a vertical column having a predetermined height; 5
- (b) a pair of superimposed brackets extending substantially horizontally and supported by said column, one of said pair of brackets being arranged adjacent the top of said column and the other of said pair of brackets being arranged adjacent the bottom of said column, each of said pair of brackets defining a plurality of holes, one of each of said plurality of holes defined by said one of said pair of brackets and one of each of said plurality of holes defined by said other of said pair of brackets being arranged 10 in registry;
- (c) a plurality of supporting rods substantially equal in length to said predetermined height extending parallel to said column, each of said plurality of supporting rods projecting through one of each of said plurality of holes defined by said one of said pair of brackets and each of said plurality of supporting rods projecting through one of said plurality of holes defined by said other of said pair of brackets; 15
- (d) a plurality of pairs of superimposed bearings, each of said plurality of pairs of bearings being slidably mounted on one of said plurality of supporting rods and having a smaller vertical spacing than said predetermined height; 20
- (e) means for fixedly securing the lower of each of said plurality of pairs of bearings to a point of one of said plurality of supporting rods; 25

- (f) a plurality of substantially flat frame structures each supported by one of said plurality of pairs of bearings and each extending in cantilever fashion away from one of said plurality of supporting rods, each of said plurality of frame structures having a height substantially equal to said vertical spacing between bearings of each pair of each of said plurality of pairs of bearings; and
- (g) a plurality of roll-supports open at the upper side thereof, each of said plurality of roll-supports having a pair of concave roll-supporting surfaces and each of said plurality of roll-supports including a pivot means having a vertical axis arranged midway between said pair of surfaces and pivotally securing each of said plurality of roll-supports to one of said plurality of frame structures adjacent the lower side thereof.
